ABSTRACT

A drawer with a thermoplastic rear wall connected to sides of the drawer, which rear wall has integral friction resistant guide means adapted to slidingly engage a wooden rail of a cabinet to align the drawer as it slides in and out of the cabinet. The thermoplastic rear wall is part of a thermoplastic panel, which panel has indicia to show where the panel is to be properly folded to form a drawer of a specified width and length with a thermoplastic rear wall and two sides joined by integral flexible hinge portions of the thermoplastic panel.

DRAWER WITH GUIDE SYSTEM

This invention relates to a drawer, such as is commonly used in furniture, kitchen cabinets, etc. More particularly, this invention relates to a drawer with a system for guiding the drawer along a linear path as it slides in and out of a cabinet or housing structure.

Drawers often have a guide system to keep them from twisting or cocking in the cabinet structure. These guide systems can take various forms, such as grooves in the sides or bottom area of the drawer, with these grooves sliding along a wooden rail fastened in the cabinet.

In the past, drawers made from wood had a serious problem because the wooden groove structure would sometimes stick and bind to the wooden guide rail, making the drawer hard to move. High humidity could cause the mating wooden rail and groove structure of the drawer to swell or warp sufficiently so the drawer could bind. Nearly everyone has at one time been frustrated by a drawer that stuck shut. When the drawer finally did open after considerably tugging, the drawer came out with such force that its contents were spilled on the floor.

Attempts to overcome this drawer-sticking problem have included waxing the guide rails, and installing metal or plastic inserts in the wooden groove structure to reduce friction. Waxing was not always satisfactory, because the wax would wear off and the drawer could again stick to the cabinet. The metal and plastic inserts, in addition to being costly themselves, usually required special holes to be cut in the drawer to receive them. Some inserts were attached with screws, nails or glue to hold them at a proper location on the drawer. All of these prior devices added substantial labor expense to the construction of a drawer.

In my invention, I have provided a simple, easily assembled drawer with a reliable friction resistant guide system integral with a thermoplastic rear wall of the drawer, which rear wall is connected to sides of the drawer. As will be explained later, the drawer's back and two sides can be injection molded in a single panel of friction-resistant thermoplastic with a guide means, such as a T-shaped notch, integrally formed at a center of the panel. Indicia on the panel show the particular locations on opposite sides of the integral guide means for folding the panel to form the back and two sides of the drawer. The guide means being of a friction-resistant thermoplastic, such as polypropylene, does not materially swell or warp with humidity, and since it is integral with the rear wall it cannot come loose from the rear wall.

Perhaps this invention can be better understood with reference to the following drawings, in which:

FIG. 1 is a perspective view of a cabinet or housing within which the drawer slides;

FIG. 2 is a perspective view of a drawer ready to be inserted into the cabinet;

FIG. 3 is a perspective view of the drawer of FIG. 2 showing the bottom and guide means structure of the drawer;

FIG. 4 is a perspective view of a panel used to form the back and sides of the drawer;

FIG. 5 is a rear elevational view of the panel for forming the back and sides of the drawer, here showing the indicia for pointing out where the drawer panel is to be folded;

FIG. 6 is an end elevational view of the panel of FIG. 5;

FIG. 7 is an elevational view of a rear wall of the drawer showing a first embodiment of the guide means at its bottom and a second embodiment of the guide means at its top;

FIG. 8 is an elevational view of the rear wall of the drawer showing a third embodiment of the guide means at its top and a fourth embodiment of the guide means at its bottom;

FIG. 9 is a bottom plan view of a drawer with an integral guide means at a bottom of the rear wall; however, here the guide means has also been joined with a friction resistant thermoplastic channel member extending between the rear wall and the front of the drawer; and

FIG. 10 is a perspective view of the thermoplastic channel member.

Referring in detail to these drawings, FIG. 1 shows a typical cabinet structure 1 into which a drawer fits. This cabinet structure is intended to be representative of housings surrounding drawers in such applications as kitchen cabinets, store fixtures, desks, furniture pieces, etc. The drawer 2 of FIG. 2 is positioned ready to slide into the housing. The drawer is confined to a rectilinear sliding movement in the cabinet by a wooden guide rail 3, which is shown as T-shaped.

As best seen in FIG. 3, the drawer has a friction-resistant thermoplastic rear wall 4 with a portion below the drawer bottom 6 defining a T-shaped notch 5 which receives the wooden guide rail 3.

In the past, in wooden drawers the notch structure would often change dimension with humidity and temperature changes, casing the drawer to stick and bind against the wooden guide rail. As previously mentioned, in an effort to overcome this problem, plastic or metal fitments were attached to the grooves to reduce friction. Some of these fitments required a special hole to be cut into the drawer bottom 6 to receive them. Others were secured to the drawer with mechanical fastening means. All of these separate plastic fitments had the disadvantage that they could come loose after continued use of the drawer.

In the present invention there is not problem of the guide means coming loose from the drawer, because the entire rear wall 4 of the drawer is of a friction-resistant thermoplastic. The drawer is formed from a friction-resistant thermoplastic panel 7, as shown in perspective in FIG. 4. The panel includes a bottom supporting structure 8, shown as a groove adjacent its lower edge, and a rigidifying upper flange 9 adjacent its top. There are two vertical flexible hinge portions 10 and 11 spaced apart. They are on opposite sides of the T-shaped notch 5 in the panel. Because the upper flange and the bottom supporting structure along with bottom flange 20 have been at least partially severed at 12 and 13 and are aligned with flexible hinge portions 10 and 11, the panel can be folded to form the back 4 and two sides 14 and 15 of the drawer. The sides and back are integrally joined together along inner surfaces of the rear corners 16 and 17 of the drawer, and forward sections of the sides are secured to a front 18 of the drawer. The panel 7 itself is described in more detail in my copending U.S. patent application entitled "Drawer," filed Dec. 23, 1968, Ser. No. 785,916.

An important feature of the present invention is the integral friction-resistant guide means of the panel and how it provides a drawer structure that is particularly easy to assemble. FIGS. 5 and 6 show the panel 7 as it comes from an injection molding machine with the T-shaped notch already molded in the friction-resistant thermoplastic. The panel also has integral thermoplastic symbols 19 indicating a linear distance in opposite directions from the T-shaped notch 5. Thus, a chart can be provided with the panels to show precisely where to cut the top flange 9, bottom supporting structure 8 and lower flange 20 to form a drawer of a particular width and length. The indicia 19 can also be used to indicate where ends of the panel should be cut to form integral flaps on the panel for joining to a drawer front, as explained in my copending U.S. Pat. application Ser. No. 785,916. Although the indicia 19 has been shown to be near the bottom supporting structure 8, it could be near the upper flange 9 or there could be two scales, one near the upper flange and one near the bottom supporting structure.

FIGS. 7 and 8 show four embodiments of the integral friction-resistant guide means. The FIG. 7 guide means can take the form of a T-shaped notch 21 or 22 at the top or bottom of a thermoplastic rear wall 23. In this figure, the T-shaped notch is shown above the upper edge 24 of the rear wall, but it could be below the upper edge as well. When there is structure 25 above the upper edge of the rear wall defining the T-shaped notch, such structure can also act as a stop by hitting a front wall of the cabinet to stop the drawer before it is completely pulled out of the cabinet structure. In FIG. 8, the integral friction-resistant guide means is in the form of a T-shaped protrusion
